UNITED STATES PATENT OFFICE.

JOHN M. MYERS, OF WOODCLIFF LAKE, NEW JERSEY.

BOOKBINDING.

1,341,575.

Specification of Letters Patent. Patented May 25, 1920.

Application filed March 8, 1915. Serial No. 11,714.

To all whom it may concern:

Be it known that I, JOHN M. MYERS, a citizen of the United States, residing at Woodcliff Lake, in the county of Bergen and State of New Jersey, have invented certain new and useful Improvements in Bookbinding, fully described and represented in the following specification and the accompanying drawings, forming a part of the

same.

This invention relates to the art of bookbinding, and the invention comprises a method wherein sheets from a loose-leaf temporary binder or other sheets are bound in a back or clamping means of metal or other suitable material and the bound sheets then secured in a cover by securing the metal back to the back piece of the cover; and devices or means constructed and adapted for use in practising said method, and the resulting or complete article.

Among the objects of the invention may be noted the provision of an improved method of and means for binding permanently any desired number of sheets of the so-called "loose-leaf" type in such manner that any attempt to remove or insert leaves may be detected, notwithstanding the fact that in certain embodiments of the invention the covers and back of the book or binder may be renewed or repaired at will; the provision of a method of and means for binding sheets whereby the waste area of the pages is minimized without sacrificing either security or mechanical strength; the provision of a method and means for binding sheets such that a substantially full opening of the bound volume is permitted to give access to substantially the entire sheet and such that when the book is open the sheets lie substantially flat throughout almost their entire length; and the provision of a book or binding in which are incorporated some or all of the above-mentioned features.

Other objects will be in part obvious from the annexed drawings and in part indicated in connection therewith by the following description of this invention.

This invention accordingly consists in the method and the features of construction, arrangement and combinations of parts as hereinafter described and specifically set forth in the claims.

A full understanding of the invention can best be given by a detailed description in connection with drawings illustrating an approved form of binding embodying the apparatus features of the invention, and such a description will now be given in connection with the accompanying drawings, in which:—

Figure 1 is a perspective of a metal back-plate, with certain parts secured thereto;

Fig. 2 is a transverse section on the line 2—2 of Fig. 1;

Fig. 3 is a longitudinal section on the line 3—3 of Fig. 1;

Fig. 4 is a perspective of a preferred form of rivet;

Fig. 5 is a sectional elevation of a com- 70 pleted binding with part of the book broken away; and

Fig. 6 is an end elevation of the bound book, partly broken away.

In order that the various features of this 75 invention may be readily understood in their relation to the prior art, it may be noted that for many years there has been a demand for means for binding together per- 80 manently sheets from loose leaf binders, pre- 85 serving the exact order of the several pages in the binding, and providing for detection of any unauthorized tampering with the sheets. Such permanent binders are useful, for example, in binding for permanent reference a series of sheets or leaves which for convenience have been kept in a temporary binder of the loose-leaf type, but which after the making of entries or records thereon is completed it is important should be 90 bound together in permanent relation in a binder that is at once inexpensive, durable and convenient to handle. The permanent binder, furthermore, should leave free at least as much of the sheet area as the tem- 95 porary binder left free; it should be easily applied without requiring expensive tools or high-grade labor; the clamping device should be so designed and proportioned as to preclude the possibility of the unauthorized removal of sheets from the binder or other changes in the composition or arrangement of sheets without detection; and it is desirable that the side covers and back piece of the cover be replaceable without the ne- 100

cessity of disturbing the permanent relation 105

of the sheets themselves, thereby adding to the useful life of the sheet holding part of the binder with its contained sheets or leaves without sacrificing the permanent construction of the sheet-securing devices.

As will be pointed out hereinafter, the method and apparatus or article of the present invention embody the above advantages, as well as other desirable features 10 which will be obvious from the following consideration of the method and structure found preferable in actual practice.

Referring now more particularly to the drawings there is illustrated at 1 a metal sheet holding back or binding piece whose length approximates the height of the leaves or sheets 2 to be bound which are shown 15 in Figs. 5 and 6. This metal binding piece comprises a transversely curved central portion 3, to the concave side of which may be riveted or otherwise secured the threaded holding members or nuts 4 and the closures 5 hereinafter more fully described. The longitudinal edges of the binding piece 1 20 are flanged as at 6, and these flanges 6 are perforated at suitable intervals as indicated at 7, 7, to receive rivets 8 passing through a counter-sunk aperture 7 in one flange, then through perforations in the sheets 2 and 25 finally through the adjacent aperture 7 in the other flange. The longitudinal edges of the flanges are beveled as indicated in Fig. 2, to avoid cutting the adjacent sheets in assembling and in the use of the bound 30 volume. As indicated in Fig. 2, the metal 35 binding piece 1 as constructed has its flanges 6 diverging, and the piece is best made of a metal of small elasticity such as aluminum. When the sheet holding back or 40 binding piece is to be applied to a set of sheets 2, the sheets are first perforated, if not already perforated, in order that the rivets 8 may pass readily therethrough; the sheets may also be trimmed, and the outer 45 edge of the set of sheets may if desired be concaved as is customary in book-binding. The binding piece 1 is then fitted against the binding edge of the sheets, with the apertures 7 registering with the perforations in 50 the leaves 2. Next the flanges are pressed and bent together until they are approximately parallel to each other and press inwardly against the leaves. Then a rivet 8 is passed through each of the registering 55 apertures in the flanges and leaves. One end of each rivet has been previously headed as at 9; the other end of each rivet may now be flattened or otherwise deformed to hold the flange, or other means may be utilized 60 for locking each rivet with respect to both of the flanges 6; and as a result, the leaves 2 become permanently and securely bound in the metal binding piece 1. Any removal of a sheet or insertion of a new sheet, or any 65 change in the arrangement of the leaves will

obviously involve either the tearing of the leaves themselves or the mutilation of every one of the rivets 8, of which there are usually from two to four according to the size of the sheets and the mechanical 70 strength required. And it will be noted that this permanence is attained by the use of the metal piece 1 and rivets 8 alone, whether or not these several parts are mounted in a cover as hereinafter indicated. It should 75 be noted that features of the present invention are likewise applicable to devices in which a temporary locking of the sheets in the metal back is desired, and in such case, the rivets would be replaced by threaded 80 posts or other suitable devices.

Ordinarily, the sheets so bound in the metal sheet holding back or binding piece will be mounted in a cover, to reduce the 85 wear and tear on the leaves during handling and to facilitate the filing of the bound volumes with the leaves horizontal or vertical as may be found preferable. In other words, the structure thus far described provides a permanent binder, inexpensive, 90 light, and durable; but it will usually be found preferable to utilize said structure in connection with a back cover and side covers of the materials used by bookbinders, in order that the leaves may withstand the 95 rough handling given to permanent records that are continually used for reference purposes, and in order that the bound volume may have the appearance of an ordinary binding of any desired style. 100

The cover construction that has been found best in practice is illustrated in Figs. 5 and 6 as comprising a back 11 usually of binder's-board, extending around the outside of the metal binding piece 1 and fitting closely over part of the flanges 6 thereof; and the side covers 12 and 13 also of binder's-board. A layer 14 of canvas or other suitable material extends from the two covers 12 and 13 and over the inside of the back 11 so that it will be between the body of the back 11 and the metal binding piece 1, said canvas serving to join together the back of the book and the side covers 12 and 13 thereof. On the outside of the back and cover elements 11, 12, 13, is provided a covering layer 15 of leather such as sheep-skin or other desired material to serve the double purpose of improving the appearance of the book, and, with the layer 14, of holding the covers flexibly to the back. For additional strength an inner layer 16 of leather or canvas extending from the side covers about the back 11 may also be provided; and a stiffening piece or spring piece 17 of, for example, several layers of paper glued together such as is commonly used in heavy leather bindings is provided so that the bending or hinge line will be back near the edge of the back 11. From Figs. 5 and 6 110 115 120 125 130

it will be clear that there is no waste thickness of the completed volume, as is the case in many prior-art structures; that is, the book of the present invention occupies a 5 space equal simply to the thickness of the leaves plus the thickness of the two covers.

With the construction thus far disclosed, there would be left exposed to dust and dirt a portion of the book between the leaves 2 10 and the concave binding piece 1. This space is preferably closed at the top and bottom of the book, by means of the closures 5 hereinbefore described as being riveted to the inner or concave side of the binding piece 1. 15 The closures 5 are located one at each end of the binding piece, and as shown are of sheet metal shaped to conform to and to overlap the curved ends of the binding piece on the one side, and to bear against the 20 edges of the leaves 2 on the other side. Each closure has an inward extension or shank 18 by which the closure is carried and the inner end of which is secured to the metal back as by being riveted to one of the holding members or nuts 4. The closure will 25 thus be free to move transversely to the back so that when the bound sheets with the metal binding piece are secured in the cover the closures will press tightly against the 30 edges of the sheets and also against the inner surface of the back of the cover, thus tightly closing the space between the sheets and the concave binding piece.

Reference to Fig. 5 will show that when 35 the covers of the book are swung apart in opening the book, the covers separate from the leaves at a point between the back of the cover and the edge of the flange 6. This insures a maximum useful surface of the 40 leaves themselves by minimizing the waste area of the leaves due to the binding construction: that is, there is necessarily a certain width of each leaf unavailable for writing or reading, and this waste portion of 45 the leaf extends from the binding edge to a point somewhat beyond the rivets 8. If the back of the book were rigid to a point beyond the edge of the holding flange 6, there would be a further waste portion of 50 the sheet width; but by providing a construction in which the side covers swing open at a point between the rigid cover back 11 and the edge of the sheet clamping means, there is no leaf-area wasted other than the 55 amount needed to allow the clamping means a firm hold upon the sheets and the sheets may be opened substantially flat over the greater part of their area. The advantages of this arrangement, over certain prior-art 60 structures in which the waste area due to binding is increased by the cover-construction, will be apparent from a comparative examination of the several devices, without further elaboration here.

65 In attaching the binder's-board back 11 to

the binding piece 1, screws 19 may be used, extending through counter-sunk holes in the board back, through the binding piece, and into the threaded apertures in the holding-members 4. If the binding piece is of 70 a material strong enough to withstand the strain of the screw-threads, the holding members 4 may be omitted, but it has been found preferable to make the metal bearing piece 1 comparatively thin and of a light- 75 weight material such as sheet aluminum, so that it does not have the desired mechanical strength for retaining the screws 19 in place. The heads of the screws 19 may be concealed as by a strip or strips of leather, 80 such as the covering layer 15 which may bear the title of the book.

The method and structure of this invention have been outlined with especial reference to a permanent binding for loose-leaf 85 sheets. It will be apparent, however, that the invention is equally applicable to a binder for sheets that have not been first used in a loose-leaf system; and in fact, many if not all of the advantageous features 90 of this invention will be attained in binding sheets of any type, and in book-binding generally.

What is claimed is:

1. The method of binding sheets which 95 comprises inserting the back edges of a set of sheets between the flanges of a metal binding piece having outwardly flaring side flanges, pressing and bending said flanges toward and against the sheets to clamp the 100 sheets together, passing rivets through said flanges and through perforations in the sheets, and deforming the rivets to hold the flanges against the sheets.

2. A book having a binding comprising 105 in combination a transversely curved metal sheet-holding back formed with flanges, said back extending over the binding edge of a set of sheets, rivets passing through perforations in said flanges and through registering 110 perforations in said sheets, whereby the sheets are permanently secured in said metal back, and hinged side covers secured to said back.

3. A book having a binding comprising 115 in combination a metal sheet-holding back flanged longitudinally, said back extending over the binding edge of a set of sheets, means for securing the sheets permanently in said sheet-holding back, an outside cover 120 comprising a binder's-board back and a side cover hinged thereto, means for securing the back of the outside cover to the sheet-holding back and means for rendering said securing means inaccessible after the book 125 is completed without mutilating the book.

4. A binding comprising in combination means for holding together permanently a set of sheets, a board-back concaved toward the sheets, means for securing the back to 130

said first means, and closures mounted upon said first means for closing the spaces at the top and bottom of the book between the back and the bound edges of the sheets.

- 5 5. A book having a binding comprising in combination a metal sheet-holding back formed with flanges extending longitudinally, said back having between the flanges the binding edge of a set of sheets and being 10 concaved in the direction of the sheets thus received, means for permanently securing the sheets between the flanges of the sheet-holding back with the flanges pressing against the sheets, a cover-back of suitable 15 material, means for securing the cover-back to the sheet-holding back, and side covers hinged to said cover back independently of the sheet-holding back.

6. A book having a binding comprising in 20 combination means for permanently holding together a set of sheets, a rigid back concaved toward the sheets, means comprising screws for securing the back to said first means, and means comprising a sheet of 25 material pasted over the heads of the screws to conceal them and prevent undetected tampering with said screws.

7. A book having a binding comprising in 30 combination a metal sheet holding back flanged to receive a set of sheets between the flanged portions and concaved toward the sheets thus received, rivets passing through 35 perforations in said flanged portions and through registering perforations in the sheets and upset or deformed to secure the sheets permanently to the metal back, and 40 closures for closing the spaces between the bound edges of the sheets and the concave part of the metal back at the top and bottom of the sheets.

8. A book having a binding comprising in 45 combination a metal sheet holding back flanged to receive a set of sheets between the flanged portions and concaved toward the sheets thus received, rivets passing through 50 perforations in said flanged portions and through registering perforations in the sheets and upset or deformed to secure the sheets permanently to the metal back, and 55 closures for closing the spaces between the bound edges of the sheets and the concave part of the metal back at the top and bottom of the sheets, said closures each secured to the metal back on the concave side 60 thereof and extending toward the adjacent end of the back and toward the bound edges of the sheets and pressing against the edges of the sheets and provided with a flanged portion extending from the edges of the 65 sheets toward the concave portion of the metal back and overlapping said concave portion.

9. A book having a binding comprising in 70 combination a metal sheet-holding back flanged to receive a set of sheets between the

flanged portions and concaved toward the sheets thus received, means for holding said flanged portions unyieldingly against the sheets and for holding the sheets in the metal back, a cover comprising a back piece and 75 side covers extending therefrom, the back piece of the cover being secured to said sheet-holding back, and end closures secured to said sheet-holding back and formed to press against the bound edges of the sheets and 80 against the inner surface of said back piece.

10. A book having a binding comprising in combination a gripping device positively 85 securing together a set of sheets, a back removably fastened to the gripping device and terminating at a line back of the forward limits of the gripping device, and side covers each hinged to said back to swing about a pivotal line behind the forward edges of the gripping device.

11. A book having a binding comprising in combination a metal binding piece provided with flanges which extend over the binding edge of the sheets, means comprising members extending through the sheets 90 and through said flanges and holding the flanges pressed against the sheets to secure the sheets together and to said binding piece, a back secured to the binding piece between its flanges, and side covers hinged to the back 95 to open and shut about lines between the bound edges of the sheets and the edges of the flanges.

12. A book having a binding comprising in combination a rigid binding piece formed 100 with flanges extending longitudinally, said binding piece having a set of sheets between the flanges, holding members passing through perforations in the sheets and 105 through registering perforations in said flanges to secure the sheets together and to the binding piece, a rigid back secured to the binding piece, and side covers hinged to said rigid back, said back and side covers being detachable from said binding piece and 110 the sheets locked therein.

13. A binding back formed of a sheet of stiff, bendable and relatively non-elastic metal shaped with edge flanges forming clamping members, said flanges diverging to 115 permit the edges of the leaves to be bound to be inserted between them and being adapted to be pressed and bent toward each other to clamp the sheets between them, and said flanges having registering openings 120 therein to receive holding members to be passed through the sheets and to have holding engagement with the flanges.

14. A binding back formed of a sheet of metal shaped with edge flanges forming clamping members, said flanges diverging to 125 permit the edges of the leaves to be bound to be inserted between them and being adapted to be pressed and bent toward each other to clamp the sheets between them, and 130

said flanges having registering openings therein to receive holding members to be passed through the sheets and to have holding engagement with the flanges, the longitudinal edges of said flanges being beveled outwardly to avoid cutting the sheets against which they bear.

In testimony whereof I have hereunto set my hand in the presence of two subscribing witnesses.

JOHN M. MYERS.
